FURNACE HEAT REGULATOR

Paul C. Timm and William P. Timm, Lincoln,
Nebr.

Application November 15, 1933, Serial No. 698,162

9 Claims. (Cl. 236—16)

Our invention relates to furnace heat regulators, one of its objects being the provision of a regulator which may be applied to any and all furnaces including those commonly known as pipeless furnaces and as semi-pipeless furnaces.

Another object of the invention is the provision of a furnace heat regulator which is sensitively responsive to the movements of expansion and contraction of the furnace itself.

10 Another object of the invention is the provision of a lever which enters through the side of the furnace jacket to contact with the furnace.

Another object of the invention is the provision of a furnace heat regulator having linkage secured to a support, the support being adapted for positioning in close proximity to the furnace jacket on the outer side thereof and being adapted to be secured to the ceiling of the basement and to the furnace jacket or frame.

20 Another object of the invention is the provision of leverage for transmitting the movements of expansion and contraction of the furnace and for greatly amplifying these movements.

Another object of the invention is the provision 25 of an adjustment for the check valve of the furnace for balancing the leakage of air into the fire box of the furnace.

Another object of the invention is the provision 30 of a furnace heat control which is provided with an adjustment for adjustably regulating the heat of the furnace.

Another object of the invention is the provision 35 of an adjustment for temporarily opening the draft valve of the furnace and including means for automatically closing the draft valve at a predetermined expansion of the furnace.

The invention also includes means for temporarily opening the draft valve of the furnace combined with means for automatically closing 40 the draft valve and combined further with means for manually closing the draft valve.

More specifically our invention includes a furnace heat regulator having a booster trip which may be manually operated from either a remote 45 position or a position in proximity to the furnace for the opening of the draft valve and combined with an automatic release for the booster trip, the release being also operable from either a remote position or from a position in proximity to 50 the furnace.

Another object of the invention is the provision 55 of a furnace heat control combined with an electrical circuit having a switch which is operable by the furnace heat control whereby the circuit may be opened or closed through an air

conditioner, an electrical fan, an indicator or rheostat or any other electrical device.

Having in view these objects and others which will be pointed out in the following description, we will now refer to the drawings, in which

Figure 1 is a view in side elevation of a furnace, a part being broken away, showing the installation of the furnace heat regulator.

Figure 1A is a perspective view of a support of slightly modified form.

Figure 2 is a view in side elevation of a portion of the regulating mechanism drawn to an enlarged scale and showing the booster trip in its latched position.

Figure 3 is a view similar to Figure 2 but showing the booster trip in its manually unlatched position.

Figure 4 is a view in end elevation showing the booster trip as it would appear when looking from the left at the end of the mechanism shown in Figure 2.

Figure 5 is a diagrammatic representation of that portion of the mechanism which may independently operate the electrical switch.

The furnace 10 is provided with the usual furnace jacket 11. The furnace is provided with openings having castings 12 and 13 for supporting the closures, the castings having the configuration of the furnace jacket 11 and being secured thereto. The closure 14 is the draft valve for controlling the inlet of air. The furnace is also provided with a furnace pipe 15 having a check damper 16 secured thereto. It is to a structure as above described to which our invention is attached regardless of whether the furnace is what is known as pipe furnace, semi-pipeless furnace or pipeless furnace. Such furnaces are installed usually in basements. The floor above is indicated above by the numeral 17 and this floor rests on basement joists 18.

The furnace heat regulator includes a support 19 which depends from one of the joists 18 or from a cleat 20 which is secured to one or more of the joists. The support 19 is secured in such position that it is in front of the furnace jacket 11 and in close proximity thereto. The support 19 terminates at its lower end immediately above the upper edge of the casting 12 and it is secured to the furnace jacket by means of a bracket 21

the lower portion of which is against the inner surface of the rim of the casting 12 or at any other convenient point below the lever 22. This arrangement provides for the rigid positioning of the support 19 relative to both the joists 18 and to the furnace. In cases where additional rigidity

is required, braces may be secured to the support 19 and to the joists 18.

Since different furnace installations vary widely, the support 19 must be adjusted in length 5 to each particular installation. This may be done by cutting off a portion of the support or the support may be made in a telescoping form similar to that shown in Figure 1A. The support consists of two members 19a and 19b having 10 a telescoping relation and being secured together by means of fastening devices 19c.

The support 19 is provided with a plurality of 15 equidistantly spaced apertures throughout its length. The lever 22 is pivotally secured at 23 to the support 19 through one of the apertures thereof. This lever is positioned on an approximate level of the dome of the furnace 10 and it is provided with a downturned inner end which contacts with the furnace dome. Above the lever 20 22 are two or more levers such as the levers 24 and 25, both pivotally secured to the support 19 and extending outwardly therefrom. A link 26 connects the levers 22 and 24, this link being an 25 expansible and contractible link as by means of a turn buckle. A link 27 connects the levers 24 and 25, the connection between the lever and link 27 being adjustable by means of a plurality of apertures in the link 25. A counterbalancing spring 28 is secured at its ends to the lever 25 and to the 30 support 19 or other fixed point, the purpose of the spring 28 being to maintain the inner end of the lever 22 in constant contact with the furnace dome. The movements of expansion and contraction of the furnace will thus be communicated 35 from the lever 22 to the lever 24 and thence to the lever 25, the movement in each case being amplified so that the outer end of the lever 25 will move through a much greater arc than the arc of the movement of the inner end of the lever 22.

For communicating the movement of the lever 40 22 to the draft valve 14 and to the check valve 16 we provide a chain or similar mechanism as shown. The lower end of the chain 29 is secured to the draft valve 14 to open that valve or to permit its closure under its own weight. Secured to the lever 25 is a bracket having lower and upper 45 idler pulleys 30 and 31. The outer end of the lever 25 has an arcuate rack 32 secured thereto, this rack cooperating with a pulley 33 concentric therewith. The rack 32 is provided with notches 50 for receiving the pawl 34 of the handle 35 projecting from the pulley 33. The notches of the rack 32 are shallow in depth and the spring on the axis of the pulley 33 permits the ready sliding of the pawl 34 from one notch to another. The pulley 33 is grooved as shown in Figure 4 55 and it is provided with a tooth 36 for engaging the chain 29 to prevent the sliding of the chain on the pulley.

The pulley 33 is secured to one of the joists 60 18 or to a suitable cleat 39. Similarly secured to one of the joists 18 directly above the hinge of the check valve 16 is another pulley 40 as well as an amplifying lever 41. The chain 29 is thus trained 65 over the pulley 30, around the pulley 33, under the pulley 31 and over the pulleys 38 and 40, its end being secured to the amplifying lever 41 at a position relatively near the pivotal point of that lever. Another chain 42 is secured at its ends to the check 70 valve 16 and to the outer end of the lever 41. The chain 42 may be adjusted in length by any suitable means such as the S-link 43. The importance of the adjusting member 43 resides in the fact that the draft through the valves 14 and 16 must be 75 balanced in order to make the furnace function

properly. There is usually more or less draft through the valve 14 even when it is in its closed position and the amount of this draft depends to a large extent on the condition of the valve 14. If the valve becomes caked or warped the draft will naturally be greater. The same thing is true of ill-fitting joints in the front of the furnace through which air may leak to the fire. For this reason the draft through the valve 14 is not constant. In making the adjustment in the chain 42 the valve 16 is carried open just sufficiently to counter-balance the leakage through the valve 14 or other ill-fitting joints. It will be apparent from the above description that any movement of the furnace dome will be communicated to the draft valve 14 and to the check valve 16 in greatly amplified form. The movements of the chain 29 and 42 are directly due to the arcuate movements of the outer extremity of the lever 25. This lever has a gooseneck at its inner end as shown in Figures 90 1 and 5 for reducing the friction in the levers. Moreover, the amplification of the movement of the chain 42 is greater than that of the chain 29. 95

The construction above described is adapted to 100 regulate the furnace heat when the furnace is functioning normally. The parts must of course be properly adjusted during the installation of our regulator. The distance between the joists 18 and the dome of the furnace 10 naturally determines the position of the lever 22. This in turn 105 determines the positions of the levers 24 and 25. The chains 29 and 42 must then be given the proper lengths and their connections with the lever 41 must be suitably adjusted to the specific installation. The links 26 and 27 must also be 110 adjusted to provide for a most suitable movement of the lever 25. The adjustments 35 and 43 do not pertain to the installation and these adjustments are designed for taking care of weather 115 conditions which may vary from day to day. The temperature of the living rooms may be varied by adjusting the lever 35 so that when it becomes desirable to maintain the temperature at a higher or lower level, the lever 35 may be suitably adjusted. Under normal operation, however, the 120 adjustment through the lever 35 is the only one required and this adjustment is necessary only when a higher or lower temperature is required for the living rooms according to the condition of the weather. If the grate is kept clear and if 125 the supply of fuel is properly replenished, no further attention is required as the chains 29 and 42 will properly adjust the two valves to keep the room temperatures sensitively at a constant 130 temperature.

Sometimes as when the fire is slow burning, it is desirable that the temperature should be raised more rapidly than would be done by the chain 29 in its automatic operation. Sometimes this may be done by proper adjustment of the lever 135 35 so as to open the valve 14 more widely. We have also provided a booster trip with automatic 140 operation for rapidly bringing about a higher furnace temperature, the trip being automatically thrown out when the furnace temperature reaches a predetermined point. The trip proper is shown at 44 in Figure 1 and it is shown more in detail in Figures 2, 3 and 4. This trip is slotted at 45 and apertured at 46 with a lip 47 immediately above the aperture 46. The trip 44 is secured to a chain 48 which is secured to the chain 29 at an intermediate point thereof as shown in Figure 1. A chain 49 is secured to the trip 44 at its upper end and this chain is trained over a pulley 50 from which it passes through the floor 145 150

into the living room. The trip 44 cooperates with a forked lever 51 which is pivotally secured at 52 to the lever 25. This lever is provided with a tine 53 for entering the aperture 46 to hold the lever 44 in its uppermost position. When tension is applied to the chain 49 the lip 47 rides over the tine 53 so that the tine 53 will enter the aperture 46. By pulling up on the chain 49 in the living room, the trip slide 44 is thus raised until it engages the tine 53 and is releasably latched in the Figure 2 position. A tension spring 54 is secured to a fixed point and to an intermediate point of the chain 49. When the trip 44 is drawn into the Figure 2 position and the grasp 15 on the chain 49 is released, the spring 54 will restore the free end portion of the chain 49 to its normal or inoperative position. A short length of chain 49' is secured to the chain 49 for convenience in raising the trip 44 from a position 20 near the furnace. A pull on the chain 49' will thus have the same effect on the trip that a pull on the chain 49 will have.

The trip mechanism further includes an idler pulley 55 which is secured to the forked lever 51. A chain 56 is secured at one of its extremities to the chain 29 and is trained under the pulley 55. At its upper extremity it is connected to an apertured link 57 which in turn is connected through a tension spring 58 to a fixed point 59. The apertures in the link 57 are numerous so as to provide a fine adjustment for the effective length of the chain 56. The chain 56 continues beyond the link 57 and terminates at a convenient position such as one of the living rooms as 35 shown in Figure 1. The link 57 is shown merely as a link in the chain 56. The tension spring 60 is secured at one end to the chain 56 and at its opposite extremity to the fixed point 59, its function being to maintain the free portion 40 of the chain 56 under tension and to restore the chain to its idle position when the tension on its outer end portion is released.

The operation of the booster trip will be evident from an inspection of Figures 2 and 3. The trip 45 slide is lifted from the Figure 3 position to the Figure 2 position by drawing on the outer end of the chain 49 or the free end of the chain 49'. The grasp on the chain is released as soon as the trip is in its Figure 2 position. At this time the 50 draft valve 14 is wide open. As the furnace warms up the outer extremity of the lever 25 is gradually depressed and the forked lever 51 is moved through an arc because of the action of the chain 56 on the idle pulley 55 pulling against the weights 55 51a. At a certain point in the movement of the forked lever 51, the tine 53 will release the booster trip 44 and thus permit the closing of the draft door 14 under its own weight. Should the temperature in the living room rise more rapidly than 60 anticipated, a pull on the chain 56 will raise the pulley 55 to swing the forked lever 51 and to thus release the booster trip 44 as shown in Figure 3. Should the chain 49 in the living room be raised accidentally to latch the booster trip 44, the parts 65 may be restored to their idle position before the increase in the draft has raised the temperature of the living room.

The adjustment through the lever 35 on the dial 32 results in a movement of the chain 29 similar to that resulting from the movement of the lever 25. It acts on both the draft valve 14 and the check valve 16. The adjustment is more or less permanent since it is seldom necessary to move the lever 35 except during changes in the 75 weather. It should be noted, however, that the

adjustment through the lever 35 affects not only the chain 29 but also the chain 56. In the position of the lever 35 shown in Figure 2, the fork 51 is in substantially horizontal position so that the lever 25 must move through almost its maximum arc before the trip slide can be released. The opposite extreme position of the fork lever 51 is shown in Figure 3 in which the tine 53 is tilted at an angle such that it cannot retain the trip slide. It will be apparent from our drawings 80 that the fork lever 51 may be adjusted into any desired position between the two extreme positions shown in Figures 2 and 3 in order to release the trip slide upon movement of the lever 25 through any desired arc within the range of the connections. The adjustment is effected by means of the lever 35 and by means of the link 57. The adjustment may be made so that the booster trip will automatically release whenever the furnace is heated past any predetermined point as indicated by the dial setting of the lever 35, the distance being governed by the adjustable link 57.

It will thus be seen that the booster provides a manual control for accelerating a slow burning fire, combined with an automatic release to prevent the rise in temperature above a predetermined point. The automatic release is adjustable in accordance with the particular installation as well as with varying weather conditions and other varying factors. When the booster is combined with an automatic control of the check and draft valves as in the present instance, it causes a rapid increase in temperature up to a predetermined point and then shuts off to permit the automatic operation of the connections between the check and draft valves of the furnace. The booster mechanism with its automatic shutoff may in fact be used alone for accelerating the rise in temperature. It is also 110 obvious that the booster mechanism may be used with other types of heating plants such as oil or gas burning furnaces or electric stoves in which an occasional acceleration of heat is required. We therefore wish it to be understood that the 115 terms in the appended claims are designed to include all mechanical equivalents to be found in heating plants of types other than the coal burning furnace which we describe.

The lever 25 may be used for opening and closing electrical circuits depending on the temperature of the furnace regardless of whether or not the connections for operating the furnace valves are employed. In Figures 1 and 5 is shown conventionally an air conditioner 61 to be automatically set into operation when the temperature reaches a predetermined minimum. The source of power is shown at 62 and this most commonly is the socket for the connection to the power or light system of the house.

In the construction shown in Figures 1 and 5, two circuits are shown, one through the air conditioner 61 and another through an indicator 63 which may be a bell or a light or any other suitable indicator or any other electrical device. 140 A lever 64 of conducting material is inserted in the circuit for contact with the two points 65 and 66 set for predetermined maximum and minimum temperatures respectively. The lever 64 is balanced in neutral position by means of the 145 springs 67 and 68. The spring 67 is connected to the lever 25 through a link 69 having a turn-buckle at its extremity for adjustment of the lever 64 relative to the two contact points. If the heat of the furnace increases the outer end of the 150

lever 25 will be depressed to bring the lever 64 into contact with the point 65 to close the circuit through the air conditioner 61. If the fire in the furnace becomes so low that it needs attention for replenishing the fuel, the lever 64 will move upwardly and at a predetermined temperature it will come into contact with the point 66. This establishes the circuit through the indicator 63 to give warning that the furnace needs attention.

10 A slight modification of the electric switch is shown in Figures 2 and 3 which employs a mercury switch 64 pivotally secured at some fixed point. This switch is balanced by means of the 15 two counterbalancing springs 67' and 68', the spring 67' being connected to the lever 25 through the link 69'. This switch is an "on and off" switch for directing the current through a single 20 device such as air conditioner or an indicator or any other electrically operated device.

Having thus described our invention in such full, clear, and exact terms that its construction and operation will be readily understood by other skilled in the art to which it pertains, what we 25 claim as new and desire to secure by Letters Patent of the United States is:

1. A furnace attachment including a substantially horizontal lever having a pivot outside the furnace jacket and in proximity thereto, said 30 lever passing through a vertical wall of the furnace jacket and having its inner extremity in contact with the furnace for lever movements in response to the movements of expansion and contraction of the furnace, means operable by said lever for opening and closing the draft valve and the check valve of the furnace in response to the expansion and contraction movements of the furnace, a remote control for manually opening the draft valve of the furnace, and means automatically operable to close the draft valve of the furnace at a predetermined furnace temperature.

2. A furnace attachment including a substantially horizontal lever having a pivot outside the furnace jacket and in proximity thereto, said 45 lever passing through a vertical wall of the furnace jacket and contacting with the furnace to respond to the movements of expansion and contraction thereof, a second lever and amplifying connections between said two levers, flexible 50 connections from said second lever to the draft and check valves of the furnace for the opening and closing thereof in response to the expansion and contraction of the furnace, a booster trip slide manually operable for opening the draft valve of the furnace, means on said second lever for latching 55 said slide to hold the furnace draft valve in open position, said means being automatically operable by the movement of said second lever for releasing said slide at a predetermined furnace temperature.

3. A furnace attachment including a lever operable by the movements of expansion and contraction of the furnace, a flexible member secured at its ends to the draft valve and the check 65 valve of the furnace and adjustably secured at an intermediate point thereof to said lever, a manually operable slide for connection with the draft valve of the furnace, a trip lever pivotally secured to said first named lever and adapted to 70 engage said slide to maintain the furnace draft valve in open position, and means automatically operable by the movement of said first named lever for the pivotal movement of the said trip lever to release said slide at a predetermined furnace 75 temperature.

4. A furnace attachment including a lever responsive to the movements of expansion and contraction of the furnace, a pulley at the outer extremity of said lever, means between the said pulley and said lever for releasably latching said pulley in adjusted position, a chain passing over said pulley and secured at its extremities to the draft valve and the check valve of the furnace, a manually operable flexible connection to the draft valve of the furnace and including a slide, a trip lever pivotally secured to said first named lever and adapted to engage said slide for maintaining the furnace draft valve in open position, and means on said chain for tilting said trip lever and to thus release said slide and to permit the furnace draft valve to assume its closed position.

5. A furnace attachment including a lever responsive to the movements of expansion and contraction of the furnace, means for transmitting in amplified form the movements of said lever to the draft valve and the check valve of the furnace, a manually operable slide connected to the draft valve of the furnace, a trip lever pivotally secured to said first named lever, means on said trip lever for releasably engaging said slide for holding the furnace draft door in open position, and means operable by said first named lever for tilting said trip lever to release said slide and to thereby permit the closing of the draft valve at a predetermined temperature of the furnace.

6. A furnace attachment including a lever responsive to the movements of expansion and contraction of the furnace, a pulley at the outer extremity of said lever, means for holding said pulley in adjusted position against rotation on its axis, a chain secured at its extremities to the draft valve and the check valve of the furnace and secured at an intermediate point thereof to said pulley, a slide having a flexible connection to the draft valve of the furnace, a trip lever pivotally secured to the said first named lever and having means for engaging said slide for maintaining the furnace draft valve in open position, a second chain actuated by the said first named chain for tilting the said trip lever on its pivot in response to the movement of the first said lever to thereby release said slide and to thus permit the closing of the furnace draft valve when the furnace reaches a predetermined temperature, said second chain being adjustable in length for governing the degree of the arcuate movement of said trip lever.

7. A furnace attachment including a lever operable by the movements of expansion and contraction of the furnace, a slide on said lever, a connection between said slide and the draft valve of the furnace whereby the lifting of said slide relatively to said lever will lift the furnace draft valve to open position, a latch on said lever for releasably holding said slide in lifted position, and means for automatically releasing said latch at a predetermined position of said lever.

8. A furnace attachment including a lever operable by the movements of expansion and contraction of the furnace, a slide on said lever, a connection between said slide and the draft valve of the furnace whereby the lifting of said slide will lift the furnace draft valve to open position, a pivoted latch on said lever for releasably holding said slide in lifted position, and tension means operable by said lever for tripping said latch to release said slide at a predetermined furnace temperature.

9. A furnace attachment including a lever having one of its ends in contact with the furnace
